UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 14,855, dated March 4, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Lady's Wrap, numbered 9,037; and I do hereby declare that the engraved prints accompanying this specification convey to any one accustomed to using paper patterns a clear understanding of how to a garment made up by the pattern will appear.

The design shows loose fronts, falling in long tabs, closing to the waist-line, and exhibiting a reversed bag-like disposal back of the tabs,

a half-fitted back, displaying an under folded 15 double box-plait at the lower end of its center seam and falling over a short skirt portion extending to the back edges of the tabs, wide square sleeves, and a standing collar.

What I claim as my invention, and desire 20 to secure by Letters Patents, is—

The design for a lady's wrap, as shown in the engraved prints accompanying this specification.

SARAH JANE SHIELS.
